US00D911387S

(12) **United States Design Patent** (10) **Patent No.:** **US D911,387 S**
Carrigan et al. (45) **Date of Patent:** **** Feb. 23, 2021**

(54) **ELECTRONIC DEVICE WITH ICON**

(71) Applicant: **Apple Inc.**, Cupertino, CA (US)

(72) Inventors: **Taylor Gerard Carrigan**, San Francisco, CA (US); **Alan C. Dye**, San Francisco, CA (US); **Jonathan P. Ive**, San Francisco, CA (US); **Wan Si Wan**, Sunnyvale, CA (US)

(73) Assignee: **Apple Inc.**, Cupertino, CA (US)

(**) Term: **15 Years**

(21) Appl. No.: **29/706,716**

(22) Filed: **Sep. 23, 2019**

Related U.S. Application Data

(63) Continuation of application No. 29/649,907, filed on Jun. 3, 2018, now Pat. No. Des. 861,037.
